(57) **CLAIM**

The ornamental design for a portion of a vehicle instrument panel, as shown and described.

DESCRIPTION

FIG. 1 is a front elevational view of a portion of a vehicle instrument panel showing my new design;

FIG. 2 is a perspective view thereof; and,

FIG. 3 is a perspective view thereof viewed from the opposite side.

The broken line showing of the left-hand boundary denotes the boundary of the claim itself and forms no part of the claimed design.
